UNITED STATES PATENT OFFICE.

JULIUS B. WANTZ, OF CHICAGO, ILLINOIS, ASSIGNOR TO VICTOR ELECTRIC CORPORATION, OF CHICAGO, ILLINOIS, A CORPORATION OF NEW YORK.

CURRENT-REGULATING APPARATUS.

1,286,850.

Specification of Letters Patent.

Patented Dec. 3, 1918.

Application filed July 24, 1916. Serial No. 110,883.

To all whom it may concern:

Be it known that I, JULIUS B. WANTZ, a citizen of the United States, residing at Chicago, in the county of Cook and State of Illinois, have invented a new and useful Improvement in Current-Regulating Apparatus, of which the following is a specification.

My invention relates more particularly to current regulators for use under conditions requiring relatively close regulation of the current throughout relatively wide variations in the current.

I have devised my improved regulator for use more especially in connection with X-ray tubes of the so-called Coolidge type wherein the amount of X-ray producing high potential current which passes through the tube is dependent on the degree to which a filament forming a portion of the cathode is heated and provision is made for electrically heating the cathode. In practice the desired range of intensity of the X-rays is obtained by varying the current for heating the cathode filament between 2.75 to 5 amperes, a relatively wide range of intensity of X-rays being obtainable by a relatively slight change in the amount of heating current supplied to the tube. In view of this fact, relatively close regulation of the heating current supplied to the cathode throughout the range of current-values, is required, if relatively close control of the tube current is desired. This close regulation of heating current requires a correspondingly close regulation of the primary current of the transformer whose secondary supplies the heating current.

According to prior practice, it was customary to use either the common form of resistance coil, or a choke coil. The common form of resistance coil, however, presented the primary disadvantage of not permitting relatively close regulation of the current between the current-values of 4.5 and 5 amperes, while permitting close control at lower current values; and the choke coil,

while permitting of the desired close adjustment for the high current values, did not permit of sufficiently rapid actuation of the movable member of the choke coil at the lower current values, to render it practicable.

One of my primary objects is to provide a regulator whereby sufficiently close regulation of the current throughout the range of values thereof, may be effected without requiring undue movement of the movable element of the regulator, during the adjustment for the lower current values. Another object is to provide an improved form of regulator which shall be simple and economical of construction and positive in operation. Another object is to calibrate the regulating apparatus in terms of strength of the heating current, or in other words, so calibrate it that the operator by looking at the apparatus and without making calculations, may determine the amount of heating current flowing through the cathode filament, this calibration being preferably in amperes, which presents the advantage of standardizing the technique furnished to the operators.

Another object is to provide mechanism whereby the many varying conditions which occur in the secondary of the transformer supplying the heating current, especially under its condition of use with an X-ray tube of the Coolidge type, and energizing currents of varying voltage, within certain limits, may be compensated for in order that the operator may determine with sufficient accuracy, the amount of heating current traversing the cathode filament in any given position of the movable element of the resistance device.

Referring to the accompanying drawings, Figure 1 is a plan view of my improved apparatus, with a portion of the top plate broken away. Fig. 2 is a section taken at the irregular line 2 on Fig. 1 and viewed in the direction of the arrow. Fig. 3 is a view in elevation of a compensating resistance for coöperation with the main re-

sistance device. Fig. 4 is a view in the nature of a diagram and partly perspective showing the circuit connections of my improved resistance apparatus when used in connection with an X-ray tube of the Coolidge type; and Fig. 5, a chart indicating the ideal relation of the increase of heating current through the cathode filament and the degree of movement of the handle of the resistance apparatus.

In the particular construction illustrated my improved apparatus comprises a casing 10 formed of a base plate 11, a top plate 12 and a cylindrical shell 13 forming the side wall of the casing, these parts being bolted together as by means of the bolts 14. The upper and lower plates 12 and 11 contain alining openings 15 and 16, respectively, 15 in which a hollow shaft 17 is journaled. The shaft 17 has rigidly secured thereto at its lower end a plate 18 having a depending boss 19 which rests against the upper side of the plate 11 and positions the shaft 17 20 against downward displacement. A similar plate 20 is rigidly secured to the upper end of the shaft 17 below the top plate 12, these plates 18 and 20 being thus spaced apart, as represented. In the construction illustrated 25 the resistance elements of the apparatus are provided in the form of coils 21 made of bare resistance wire wound spirally upon cylindrical members 22, preferably tubular, and formed of insulating material, such as porcelain, or of metallic tubing covered with insulating material. The tubes 22 are grouped about the axis of the shaft 17 in an annular series and are rigidly held at their opposite ends to the plates 18 and 30 20 in any desirable manner. In the arrangement shown each of the plates 18 and 20 contains a series of apertures 23, these apertures being equi-distantly spaced and arranged in an annular series about shaft 17, 35 these apertures in these two plates alining and the portion of the wall of each being preferably formed of a springy section 24 partially cut from the plate carrying it and coöperating with the screw 25. The ends of 40 the tubes 22 project through the openings 23 and are rigidly clamped in place by the screws 25. This method of clamping allows each unit to be moved individually in the direction of its greatest length so that the 45 winding of resistance material on the unit is in a position in which they coöperate with the wiper 38.

The resistance coils 21, which are herein-after more fully described, are electrically 50 connected in succession, the terminal of the last coil, represented at X in Fig. 4, being connected with a section of a switch device represented at 26, secured to, and insulated from, the plate 18. This switch device 26,

which is provided as the means for opening 55 and closing the circuit through the resistance coils, comprises, in the form shown, two spring members 27, of conducting material, which are normally in engagement with each other under their spring tension and 60 are connected, respectively, with one of the terminals of the coil X and with a ring 28 of current-conducting material secured to the bottom of the plate 18, as by screws 29, and insulated from this plate as shown, this 65 ring contacting with a pair of spring fingers 30 secured to the base-plate 11 and connected with a binding-post 31 of the resistance apparatus.

The switch-controlling member comprises 70 a rod 32 slidable in a longitudinally extending bore 33 in the shaft 17 and carrying a laterally-projecting pin 34 which moves in a slot 35 in the shaft 17 and projects into the space between the members 27 75 at which portion it carries a sleeve 36 of insulating material, the device just described operating when the rod 32 is pulled upwardly to the position illustrated in Fig. 2, to separate the switch members 27 and break 80 the circuit.

In the particular arrangement illustrated, the coils 21 and the parts supporting them are adapted to be rotated about the axis of the shaft 17 for controlling the amount of 95 current passing through the coils, as through the medium of a hand-wheel 37 of insulating material, rigidly connected with the upper end of the shaft 17, the coils 21 coöperating with a relatively stationary contact member, or wiper, 38 which is preferably of the form illustrated and constructed of current-conducting material. As shown, the contact 38 is provided with a sleeve-portion 39 journaled on a shaft 40 rising from the plate 11. 100 The sleeve 39 rests upon a collar 41 secured to this shaft and connects at its upper end with one end of a torsion spring 42 which surrounds the rod 40 and connects at its opposite end with a collar 43 secured to this 105 rod, the arrangement of the parts being such that the contact 38 extends in an inclined position relative to the axis of each coil 21 and is of such length and inclination that it will always be in contact with one of the 110 coils 21, regardless of the adjustment of these coils about the axis of the shaft 17, it being preferred that these parts be so arranged that in the revolving of the coils 21 in either direction the contact 38 will engage with the beginning or end of one coil just before it disengages the beginning or 115 end of the preceding coil, as the case may be, depending upon the direction in which the coils are revolved, so that there will not be 120 a break in the circuit in any position of the coils relative to the contact device. The arrangement of the spring 42 is such that 125

through the turning action produced by it on the sleeve 39, the contact member 38 is caused at all times to press against the coils 21 with the desired degree for insuring proper electrical contact therebetween. The contact device 38 is electrically connected through the shaft 40, wire 71, wire 72 and compensating resistance 73 connected with these wires, to the other terminal 44 of the 10 rheostat.

According to the preferred form in which I desire to provide my improved regulating apparatus, provision is made for so proportioning the movement of the adjustable element of the regulator relative to the control of the secondary current of the transformer associated with the regulator that with a load of given characteristics the variation in the secondary current value will be constant 15 for a given movement throughout the range of movement of this element of the regulator. In other words, the movement of the movable element of the regulator throughout a given number of degrees from any position relative to the stationary contact device will produce the same variation in current value. This result is accomplished, according to the preferred illustrated embodiment of my invention, with sufficient accuracy for practical purposes, by so constructing the coils 21 that their resistances are such that the introduction into or removal of any one coil into or from the circuit will always result in the same increase or decrease in heating current. In other words considering the nine coils 21 20 illustrated in the drawings, and which appear to be the proper number to be employed under all commercial conditions, though they may be varied in number as desired, or other forms of resistance provided each coil is so wound and is so constructed that in the movement of any one of them entirely across the contact 38 the increase or decrease 25 in current passing from the secondary of the transformer through the cathode filament of the tube connected therewith, as the case may be, is the same.

In practice, any suitable method may be followed in determining the amount of resistance that each resistance coil 21 should present in order that the result, or substantially the result, above referred to may be accomplished. In view, however, of the many variables which exist in the secondary circuit of the transformer, especially where it forms a part of an X-ray system in which a Coolidge X-ray tube is employed, I prefer to determine the amount of resistance necessary to be furnished by each coil, by the following method: Take, for example, the case illustrated in the drawing wherein nine of the coils 21 are employed, the centers of these resistance units being equi-distant,

each coil, relative to the contact device 38, 65 would have an electrical contact surface equal to $\frac{360}{9}$ or 40° . So far as the coils are concerned the range of current passing from the secondary of a standard transformer through the cathode filament of a standard Coolidge tube, as is the case in the particular example illustrated, is from 2.75 amperes to 5.25 amperes, or a difference of 2.5 amperes. Of this amount the range 75 from 2.75 to 5.15 is only available in the device as preferably constructed, the other .10 amperes being unusable because of the stop device hereinafter referred to. If each resistance unit is to produce uniform variation 80 in the heating current, each must decrease the current a given amount, which in the case illustrated would be equal to

$$\frac{2.5}{9} = .278 \text{ amperes.} \quad 85$$

A resistance unit containing about twice as much resistance as it is thought necessary is first made by winding resistance wire on a relatively long tube, not shown, of small diameter. The spiral thus formed would be connected at one end to one of the primary terminals of a transformer for the cathode filament of a Coolidge tube. The other primary terminal of this transformer and a 90 contact which can be moved along the wire of the last-referred-to spiral for electrical contact therewith, are connected with the terminals of an alternating current line having a slightly lower voltage than a standard line in which an ammeter is included to measure the current strength. The terminals of the secondary of the said transformer are connected with the terminals of the cathode filament of a Coolidge tube and an ammeter is placed in series with this filament. The operator then moves the movable contact along the resistance spiral to cut resistance out of the primary circuit of the transformer until the said ammeter in 100 the secondary circuit registers 2.75 amperes. The point at which this value of current flows is then marked on, or relative to, the resistance spiral and the reading of the ammeter in series with the primary circuit of 105 the said transformer, is noted. The movable contact member is then moved farther along the said resistance spiral until the ammeter in the secondary circuit of the transformer shows that the current has been 110 increased by .278 amperes, whereupon the operator makes a mark on said resistance spiral or on something adjacent thereto, indicating this position of the movable contact member relative to the coil. The operator 115 then continues to increase the current by .278 ampere steps until practically all of the resistance is out of circuit when the heating 120 125

current will be very close to 5.25 amperes. With each operation of marking the points on the resistance spiral with which the movable contact registers for each increase of 5 .278 amperes in secondary current, the operator carefully notes the value of the primary current. The amount of resistance cut out by each of the said successive steps is then measured and thus is determined the 10 amount of resistance each of the respective coils 21 of the regulator, should have. With this information before the one constructing the instrument, the windings for each coil 21 are calculated so that each will 15 have the required resistance and also have sufficient cross-sectional area to carry the maximum current without heating to an objectionable extent, as will be well understood in practice. The amount of resistance 20 wound on these units may be varied to cause the coils 21 to present the desired amount of resistance, either by using different sizes of wire or wire of different composition or changing the diameter of the spiral or varying 25 the number of turns on the unit, or a combination thereof as desired.

By preference the apparatus is provided with a scale, illustrated at 45 and carried by the rotatable element of the apparatus, 30 namely, that which is formed in part of the coils 21. This scale reads directly in amperes of heating current and is uniformly graduated from 2.75 to 5.15. The indicator 46 on the stationary part of the casing 35 operates with the scale 45, the indicator, with a portion of the scale, being viewable through an opening 47 in the plate 12. The scale 45 is so mounted with reference to the relatively stationary contact 38 and to the 40 indicator 46 that under standard conditions, namely, with a given voltage across the resistance coils 21 and the transformer in a circuit with a standard cathode filament of a Coolidge tube, the scale will indicate directly in amperes the value of the heating 45 current.

To prevent the rotatable element of the apparatus from rotating in an anti-clockwise direction in Fig. 1 from a position in 50 which the indicator registers with the marking 2.75 wherein all the resistance of the apparatus is in circuit, to a point in which all of the resistance is cut out of circuit, I provide the stop-device hereinbefore referred to and represented at 48 which projects upwardly through an opening in the 55 plate 11 and co-operates with a lug 49 depending from the plate 18.

Reference has been made to the compensating resistance 73. This resistance, which is very desirable under general commercial conditions, is provided for the purpose of compensating for variations in the voltage of the service lines through which the trans-

formers supplying the heating current to 65 the Coolidge tubes, are energized, and compensating for variations in the resistance of the cathode filament of the Coolidge tube. This compensating resistance, when employed, may take any desired form, that 70 shown comprising a resistance unit 50 formed of bare resistance wire spirally wound upon a tube 51 covered with insulating material, a plug 52 in the lower end of the tube, a threaded attaching device 53 75 extending through the plug and secured to, and insulated from the plate 11 of the casing, the fastening device referred to extending downwardly through the tube 51 at a U-shape section 54 thereof and a slidably 80 contact device 55 on the member 53 exterior of the tube 50 and movable along, and in engagement with, the bare wire forming the coil 50. The wire 71 connects with the lower terminal of the coil 50 and the wire 72 electrically connects with the member 53 and consequently is electrically connected with the contact 55.

In installing the described regulator apparatus, as the current controller for the 90 cathode filament of a Coolidge tube, the binding posts 31 and 44 of the apparatus would be connected by wires 56 and 57, with one of the terminals of the alternating current generator 58, or any other source of alternating current, and one of the terminals of the primary 59 of a transformer, the other terminal of the primary of this transformer being connected with the other terminal of the generator 58, or other power source. 95 The terminals of the secondary 60 of the said transformer are connected with the terminals of the cathode filament 61 of a Coolidge tube represented at 62 and in series with which is an ammeter 67. One of the 100 terminals of this filament is connected by a wire 63 with the high potential rectifier 68 usually employed to supply the desired high potential current for operating the tube 62, the rectifier 68 being energized by the 105 secondary 64 of the high potential transformer through the medium of the wires 69 and 70. The primary 65 of this transformer would be connected with the alternating current line, as is well understood in the art, 110 and the other terminal of the rectifier 68 is connected by a wire 66 with the anode of the tube 62.

With the apparatus set up as just described, the operator would set the regulator 120 device so that the indicator 46 would register with any of the ampere readings on the scale 45 and this reading would check with the reading of the ammeter 67. If these 125 readings do not correspond, the operator adjusts the contact 55 along the coil 50 until the readings do correspond, and with this adjustment once made the readings on the

scale 45 will correspond with the said ammeter readings sufficiently closely for all practical purposes.

In Fig. 5 I have illustrated, by a diagrammatic chart, the relation between the variation of heating current and the movement of the movable part of the regulator apparatus. From this chart, which shows the ideal curve, it will be noted that for any given movement of the coils the current variation is a constant, the curve represented at Y being substantially a straight line.

The greater the number of individual coils the device is made up of the closer will the curve for that device approach a straight line. Experience has shown that subdividing the device into a greater number of coils than nine merely adds complications to the manufacturing process without any great gain of fidelity of control. The curve obtained from a device having nine coils is sufficiently close to a straight line for the work the device is to perform.

The switch-device 26, operated from the stem 32, presents a means whereby the circuit in which the resistance apparatus is located may be conveniently opened and closed at will, the grouping of this switch-operating member and the handle 37 particularly adapting the apparatus for X-ray work.

While I have illustrated and described a particular construction in which my invention is embodied, I do not wish to be understood as intending to limit it thereto, as the same may be variously modified and altered without departing from the spirit of my invention.

What I claim as new, and desire to secure by Letters Patent, is:

40 1. In a current regulator, the combination of resistance units mounted to rotate, and a relatively stationary contact member supported to engage said units in succession as the latter are rotated and contact therewith at different points in progression along their length.

2. In a current regulator, the combination of resistance units mounted to rotate and electrically connected together in succession, and a contact member supported to extend in an inclined position relative to the axes of said units and contact with the latter in succession when said elements are rotated, at different points in progression along the latter.

3. In a current regulator, the combination of a plurality of units formed of spirally-wound resistance material electrically connected together in succession, and a relatively stationary contact member the contact surface of which inclines relative to the axes of said units and engages with the latter at different points lengthwise of the same in succession.

4. In a current regulator, the combination of units rotatably mounted and formed of spirally-wound resistance material, a relatively stationary contact member having a contact surface extending at an angle to said units and adapted to contact therewith, and means for rotating said units.

5. In a current regulator, the combination of resistance units and a contact member movable relative to each other, said contact member supported to be movable toward and away from said units, means for yieldingly pressing said contact member into engagement with said units, said contact member opposing the sides of said units and arranged to engage the latter in succession at different points in progression along their length in the relative movement of said units and member.

6. In a current regulator, the combination of a plurality of rotatably supported resistance units, and a relatively stationary contact member coöperating with said units and having a rotatably mounted section with a contact surface which extends at an angle to the axes of said units.

7. In a current regulator, the combination of a plurality of rotatably supported resistance units, and a relatively stationary contact member coöperating with said units and having a rotatably mounted section with a contact surface which extends at an angle to the axes of said units, and means for holding said contact surface against the opposing surfaces of said resistance units.

8. In a current regulator, the combination of a plurality of rotatably supported resistance units, and a relatively stationary contact member, coöperating with said units and having a rotatably mounted section with a contact surface which extends at an angle to the axes of said units, and spring means for holding said contact surface against the opposing surfaces of said resistance units.

9. In a current regulator, the combination of a rotatably mounted shaft, and means on said shaft for mounting resistance units thereon, and adjustable to permit the said units to be adjusted in a direction parallel to the axis of said shaft.

10. In a current regulator, the combination of a rotatably mounted shaft, plates mounted on said shaft, resistance units, and means on said plates for holding said units thereto constructed and arranged to permit of the adjustment of said units in a direction parallel to the axis of said shaft.

11. In a current regulator, the combination of means for varying the amount of current passing through the regulator and including an operating member, means for opening and closing the circuit through said regulator, and a second operating mem-

- ber for controlling said last-named means, mounted on said first-named operating member.
12. In a current regulator, the combination of means for varying the amount of current passing through the regulator and involving a tubular shaft provided with a handle, and means for opening and closing the circuit through said regulator including a shaft located in said tubular shaft and carrying a handle by which it may be operated.
13. In a current regulator, the combination of means for varying the amount of current passing through said regulator and including a tubular shaft provided with a handle, electric current-conducting members, a shaft located, and movable, in said tubular shaft, and means on said second-named shaft for controlling the position of said electric current-conducting members relative to each other.
14. In a current regulator, the combination of means for varying the amount of current passing through said regulator and including a tubular shaft provided with a handle, a second shaft located, and movable, in the opening in said first-named shaft, electric current-conducting members, and an insulated projection on said second-named shaft operating when the latter is shifted, to control the position of said electric current-conducting members relative to each other.
15. In a current regulator, the combination of a casing consisting of a pair of plates spaced apart, a separating member between said plates, means clamping said plates against said separating member, and a plurality of resistance units and a contact member rotatable relative to each other, said plates forming the bearings for the rotatable element of the regulator.
16. In a current regulator, the combination of a casing consisting of two plates spaced apart, a separating member located between said plates, bolts clamping said plates against said separating member, a contact member, and a plurality of resistance units arranged to engage said contact member, rotatably mounted in said casing.
17. In a current regulator, the combination of a plurality of resistance elements and a contact-member rotatable relative to each other, a dial mounted on the rotating member and calibrated proportional to the strengths of current obtainable through the circuit controlled by the regulator, and a stationary indicator coöperating with the graduations on said dial.
18. In a current regulator, a contact member, an indicator, a graduated scale coöperating with, and movable relative to, said indicator, and a plurality of resistance elements movable with said scale and coöperat-
- ing with and movable relative to, said contact member.
19. In a current regulator, the combination of relatively movable members one of which comprises a plurality of resistance elements and the other of which is a contact member for contacting with said elements, and current-indicating means including co-operating members one of which is a scale uniformly calibrated in amperes, one of said last-named members being movable with the movable one of said first-named members and the other of said last-named members being relatively stationary.
20. In current regulating means, a wound rotatable current-carrying member and a co-operating stationary member and current-indicating means including co-operating elements one of which is a graduated scale having an indicating point which registers with the other of said elements when said current-regulating means passes a minimum value of current, a stop on said movable member and a co-operating relatively stationary stop serving to prevent the movement of the rotating element of said current-indicating means in one direction beyond said point of minimum current.
21. In a current regulator, a wound rotatable current-carrying member, a co-operating stationary member, means whereby said first-named member is rotated with respect to said second-named member, a third member mounted on said first-named member to be rotatable with it, reference marks on said third member, a stationary indicator coöperating with said reference marks, and means for opening and closing the circuit through said regulator.
22. In a current regulator, a wound rotatable current-carrying member, a co-operating stationary member, means whereby said first-named member is rotated with respect to said second-named member, a dial mounted on said first-named member to be rotatable with it, reference marks on said dial, a stationary indicator coöperating with said reference marks, and means for opening and closing the circuit through said regulator.
23. In a current regulator, a casing, a wound rotatable member and a stationary coöperating member inside said casing, a third member mounted on said rotatable member so as to be rotatable with it, reference marks on said third member, an opening in said casing, a stationary indicator in said opening coöperating with said reference marks, and switch mechanism to open the circuit through said regulator.
24. In a current regulator, the combination of a plurality of resistance elements and a contact member rotatable relative to each other, a dial mounted on said rotatable member and calibrated in accordance with the strength of the current passing through a

load of given characteristics in circuit with the regulator, and a stationary indicator cooperating with the graduations on said dial.

25. In a current regulator, the combination of three or more resistance elements arranged in a group and rotatable as a unit, a contact member stationarily mounted relative to said resistance elements, and means urging said contact member into contact with said elements.

26. In a current regulator, the combination of three or more resistance elements in the form of coils arranged in a group and mounted to rotate as a unit, a contact member stationary relative to said coils and adapted to engage the sides of the coils, and means urging said contact member into contact with the coils in the rotation of the latter. 15

J. B. WANTZ.
